UNITED STATES PATENT OFFICE.

GEORGE G. WARD, OF BROOKLYN, NEW YORK.

DESIGN FOR THE ORNAMENTATION OF LETTER-HEADS, &c.

SPECIFICATION forming part of Design No. 17,977, dated December 20, 1887.

Application filed September 19, 1887. Serial No. 230,153. Term of patent 14 years.

To all whom it may concern:

Be it known that I, GEORGE G. WARD, of Brooklyn, in the county of Kings and State of New York, have invented and produced a new 5 and original Design for Letter-Heads, Envelopes, Cable-Blanks, &c., of which the following is a specification, reference being had to the accompanying drawing, forming a part thereof, in which a fac-simile of my design is to be shown.

The leading feature of my design consists in the representation of the Atlantic-Ocean half 15 of the terrestrial globe, irregular lines being shown as extending across the said ocean, and the whole being surrounded by a cable-like

border so located as to leave a margin directly about the central representation.

I claim—

The design for the ornamentation of letter-heads, envelopes, cable-blanks, &c., herein 20 shown and described, the same consisting of the representation of one-half of the terrestrial globe traversed by irregular lines and surrounded by a cable border, substantially as described.

GEORGE G. WARD.
